(57) **CLAIM**

The ornamental design for an optical fiber connector, as shown and described.

DESCRIPTION

FIG. 1 is a front view of an optical fiber connector of our new design;

FIG. 2 is a rear view of the optical fiber connector of FIG. 1;

FIG. 3 is a top plan view of the optical fiber connector of FIG. 1;

FIG. 4 is a bottom plan view of the optical fiber connector of FIG. 1;

FIG. 5 is a right side view of the optical fiber connector of FIG. 1;

FIG. 6 is a left side view of the optical fiber connector of FIG. 1;

FIG. 7 is a front, top plan and left side perspective view of the optical fiber connector of FIG. 1;

FIG. 8 is a front, bottom plan and left side perspective view of the optical fiber connector of FIG. 1;

FIG. 9 is a rear, top plan and right side perspective view of the optical fiber connector of FIG. 1;

FIG. 10 is a sectional view taken along the line 10-10 of the optical fiber connector of FIG. 6;

FIG. 11 is an enlarged view defined by the lines 11-11 and 11'-11' of the optical fiber connector of FIG. 8;

(Continued)

FIG. 12 is an enlarged view defined by the lines 12-12 and 12'-12' of the optical fiber connector of FIG. 8; FIG. 13 is an enlarged view defined by the lines 13-13 and 13'-13' of the optical fiber connector of FIG. 9; and, FIG. 14 is a perspective view showing the use state of the optical fiber connector of FIG. 1.

The features shown in evenly-dashed broken lines depict environmental subject matter only and form no part of the claimed design. The dot-dash broken lines in the drawings represent the bounds of the claimed subject matter, the dot-dash broken lines, themselves forming no part thereof.
